(57) **CLAIM**

I claim the ornamental design for a brush cutting machine, as shown and described.

DESCRIPTION

FIG. 1 is a left back side perspective view of the brush cutting machine;

FIG. 2 is a partial back right side perspective view of FIG. 1 for convenience of illustration;

FIG. 3 is a partial left side view of FIG. 1 for convenience of illustration;

FIG. 4 is a partial left side view of the design shown in FIG. 1;

FIG. 5 is a partial front side view of FIG. 1 for convenience of illustration;

FIG. 6 is a partial perspective left side view of FIG. 1 for convenience of illustration; and,

FIG. 7 is a partial topside view of FIG. 1 for convenience of illustration.
